RADIANT HEATER

William E. Cranston, Jr., Los Angeles, Calif., assignor to Thermador Electrical Manufacturing Company, Los Angeles, Calif., a corporation of California

Application January 20, 1947, Serial No. 723,193

2 Claims. (Cl. 219—34)

1

My invention relates in its broadest aspect to a radiant type wall heater having an electrical resistance unit as its source of heat and adapted to be installed flush with the surface of a wall. More specifically my invention relates, and has to do with, the details of construction which permit locating a control switch adjacent the top of the heater, but in thermal isolation from the rest of the heater.

Radiant type wall heaters of the general type herein described have been generally known and widely used in the construction industry. However, heretofore it has always been necessary to put the control switch at the bottom of the heater. Such a location was highly inconvenient in that it required stooping to operate the switch. This location was made necessary because of the fact that heretofore known construction would allow the switch if placed at the top of the heater to become overheated by the heat conducted and convected from the resistance unit, thereby resulting in early failure of the switch due to thermal decomposition.

As is well known, most modern building codes do not permit installation of electrical equipment without the approval of the Underwriter's testing laboratory. As radiant type heaters of this classification have heretofore been constructed, the Underwriter's testing laboratory would not approve the location of a switch in the top of the heater.

It is an object of my invention to produce an electrical radiating heater of the full length type wherein the switch may be placed at the top of the heater for ease and convenience of operation.

It is a further object of my invention to so construct this type of heater that even though the switch is placed at the top of the heater it is, for all practical purposes, thermally isolated from the source of heat; therefore, not subject to thermal failures. Heaters of the type herein described containing the details of the constructions to be hereinafter explained, have been approved by the Underwriter's laboratory for general use.

With these and other objects in view, the invention consists in the construction, arrangement and combination of the various parts of the device whereby the objects contemplated are attained, as hereinafter set forth, pointed out in the appended claims, and illustrated in the accompanying drawings.

In the drawings:

Figure 1 is a front elevation of a heater embodying the principles of my invention.

2

Figure 2 is a back elevation of the heater shown in Figure 1.

Figure 3 is a side elevation, partially in section, of the heater shown in Figure 1.

5 Figure 4 is a sectional view taken on line 4—4 of Figure 2.

Figure 5 is a view taken on line 5—5 of Figure 2.

10 Figure 6 is an enlarged sectional view taken on line 6—6 of Figure 1.

Figure 7 is a fragmentary sectional view taken on line 7—7 of Figure 6.

Figure 8 is a partial sectional view taken on line 8—8 of Figure 6.

15 Figure 9 is a fragmentary sectional view taken on line 9—9 of Figure 8.

Figure 10 is a fragmentary section of a mounting post used to mount the resistance unit.

Referring more specifically to Figures 1—3 inclusive, my invention includes generally a can or electrical outlet box 10 adapted to be installed within the partition of a wall, a heat reflector 11, an electrical resistance unit 12, switching means 13 connected in electrical series with the electrical resistance unit 12, and a cover or guard 14.

The outlet box 10 is of standard construction and comprises a substantially rectangular all-metal box having an opening 15 in the top or any other convenient location adapted to receive an electrical conduit or cable (not shown), and is formed with outwardly projecting flanges 16 (see Figure 6). The heat reflector 11 is substantially semi-cylindrical in shape and is formed of any material suitable to withstand the heat 30 generated by the electrical resistance unit 12 and which will act as a heat reflector. The reflector 11 is closed on both ends by a cap 17 which is substantially semi-circular in shape and is formed with an upturned mounting flange 18 35 (see Figures 6 and 8). The cap 17 is secured to the reflector 11 by means of sheet metal screws 19 (see Figure 2) and by a return lip 20 extending the full length of each side of the reflector 11. The end plate 17 is also formed with substantially 40 radially extending projections 21 which abut against the electrical outlet box 10 and act as spacers for the proper installation of the heater. The flange 18 extends around the periphery of the spacing extensions 21 thereby adding strength to the spacers. The return lip 20 is 45 formed with a plurality of slots 22, the purpose of which will be explained later.

The cover plate 14 is substantially rectangular in shape and is formed with two principal sections, that is, a grilles or louvered section comprising 50

55

ing a plurality of transverse bars 30 spaced to define a plurality of radiant heat passing openings 31 and a switch mounting section. The heat passing section is secured to a mounting flange 32 by a plurality of substantially narrow connecting sections or webs 33 which define a plurality of openings 34. The transverse bars 30 are arcuate in shape and are formed with an extruded or upturned edge 35. The arcuate shape and the upturned edge add strength to the structure and permit the manufacture of the cover plate 14 of a relatively light gauge material. The web 33 and holes 34 are also formed with an extruded or upturned edge 36 which permit the use of a relatively light gauge material and also narrower sections in the web 33. The mounting flange 32 is formed with a plurality of apertures 37 adapted to receive mounting screws 38.

Spaced on the upturned edges 35 to correspond with the spacing of the slots 22 in the return lip 20 are a plurality of ears 39 which are adapted to be inserted through the slots 22 and then crimped over to hold the reflector 11 securely in position on the guard 14.

The switch mounting section of the cover plate 14 is located at the top of the cover plate 14 and is provided with a baffle 40 having substantially the same shape as the inside dimensions of the outlet box 10 and is adapted to isolate the switch 13 from any convection currents arising from the surface of the reflector 11. The baffle 40 is spaced above the end plate 17 so that one of the plurality of openings 31 is located between the baffle 40 and the end plate 17, thus permitting the escape of any convection current. The switch mounting section is connected to the heat passing section by relatively narrow webs 41. The webs 41 are bounded by an extruded lip 42 which also permits the use of a relatively light gauge material and a much narrower section. The switch mounting section is also formed with an opening 43, the purpose of which will be understood later.

The baffle 40 is substantially L-shaped having a projecting heel 44 adapted to act as a spacer for the switch mounting foot 45 in a position remote from the cover plate 14. The baffle 40 is secured to the cover plate 14 by spot welding the spacing heel 44 to the cover plate 14 or by any other suitable means.

Referring to Figure 10, I have illustrated the method preferred by me for securing the resistance unit 12 in place with respect to the reflector 11. The means for mounting resistance unit 12 comprises a ceramic post 70 formed with a peripheral groove 71 and a longitudinal bore 72. The ceramic post 70 is inserted through a hole 73 punched at spaced intervals through reflector 11 along its midline and having extruded or upturned edges 74. After the ceramic post 70 is inserted through the hole 73 the upturned edges 74 are deformed downwardly thereby crimping into the peripheral groove 71 of the ceramic post 70, thus securely holding it in place. A binding wire 76 is formed in the shape of a cotter pin having a loop 77 on one end thereof adapted to fit over and hold the wire of the resistance coil 12. The binding wire 76 is inserted through the longitudinal bore 72 and the ends 78 and 79 bend outwardly to prevent the wire from falling out of the bore 72.

The switch 13 may be of any suitable commercially available electrical switch having sufficient current carrying capacity to withstand the load of the resistance unit 12, and should be provided

with terminals 60 and 61 and an operating handle 62. The switch 13 is mounted by means of screws 63 on the spacing foot 45 and is spaced with heat insulating washers 64 so that the end 5 of the operating handle 62 is flush with the outside surface of the mounting plate 14, thereby preventing the accidental operation of the switch by anyone who happens to be passing.

It will be noted that due to the construction 10 herein described, the switch 13 is in substantial thermal isolation from the heat source of the heater which permits the installation of the switch 13 in such a desirable position as the top 15 of the cover plate 14. As will be readily understood in the operation of the heater, the bars 30 will absorb some of the radiant heat from the heating element 12. However, due to the relatively narrow section of the webs 33 and 41, a relatively small amount of heat is conducted to either the 20 mounting flange 32 or the switch mounting section of the cover 14 so that the area surrounding the switch operating handle 62 will not become overheated and will not interfere with the operation of the switch 13. The switch 13 is further 25 thermally conductively isolated from the grills 30 and from any heat radiated by the resistance unit 12 in that the only heat which can reach the switch 13 by means of conduction must pass through the screws 63. When it is understood 30 that relatively little heat is conducted into the switch mounting section of the cover plate 14, it will be seen that the amount of heat conducted through the screws 63 to the switch 13 is negligible.

It will further be seen that the switch 13 is 35 thermally convectively isolated from the source of heat or any heat generated by the resistance unit 12 which may be absorbed by the back of the reflector 11 and conducted upwardly by convection currents because of the baffle 10 and the opening 31A located between the end plate 17 and the baffle 40.

One of the principal advantages of a heater 40 constructed according to the proportions and details disclosed in the drawings is that the heater can be provided tall enough to supply radiant heat to substantially the entire body length of the user without making it unduly wide. The 45 general commercial practice in manufacturing 50 this type of heater has been to make the heater approximately four feet high and position the base thereof substantially at the floor level, thereby placing the switch 62 four feet from the floor.

In view of the fact that this type heater is 55 usually intended for installation in bathrooms, and in view of the further fact that most modern apartments and small bungalows contain 60 bathrooms which tend to be crowded, the heater disclosed herein is ideal in that it can be placed in confined areas and still effectively heat the body of those desiring to use it.

It will thus be seen that I have accomplished 65 the objects originally sought, that is, the production of a radiant-type heater which can be placed in confined areas, which would otherwise present a difficulty in stooping to the bottom to turn the heater off and still render the control means readily accessible. A further advantage 70 lies in the fact that in view of the height of the switch, children under the general age of four are not able to turn on the switch and are, therefore, protected against serious injury to their hands.

75 While I have herein shown and described my

invention in what I have conceived to be the most practical and preferred embodiment, it is recognized that departures may be made therefrom within the scope of my invention, which is not to be limited to the details disclosed herein, but is to be accorded the full scope of the claims so as to embrace any and all equivalent devices.

Having described my invention, what I claim as new and desire to secure by Letters Patent is:

1. A flush-type electric wall space heater comprising: a substantially impervious sheet metal box adapted for vertical installation in a wall recess, and when in such position including a back, top, bottom and sides and being open at the front, an impervious concave reflector comprising a vertical concave reflector member and substantially flat top and bottom closures and being open at the front, said reflector being mounted in said box to define a passage between the lower end of the reflector and the bottom of the box, a vertical passage between the back and sides of the reflector and the back of the box, and a passage between the top of the reflector and the top of the box, said passages being intercommunicating, an impervious substantially horizontal partition across said box near its upper end, the last said passage being defined by the upper face of the reflector top and the lower surface of said partition, open communication from the front of the reflector and box assembly at the bottom thereof leading into the first of said passages and at the top thereof leading from the last of said passages, whereby convection currents may enter below said reflector and travel upwardly between said reflector and said box and be exhausted at the upper forward region of said box and reflector, an electric switch chamber being formed at the upper end of said box by said horizontal partition in the upper terminal parts of said box, an electric resistance heating element mounted in said reflector, electric wiring for said heating element coupled with said switch, and a protective flush-type grill adapted to be mounted upon the wall adjacent the boundaries of the wall recess and in direct association with said box and reflector assembly, said grill being formed with openings near the top and bottom communicating with the said top and bottom horizontal passages which are adapted to convey convection currents.

2. A flush-type electric wall space heater having a length substantially greater than its width comprising: a substantially impervious sheet metal box adapted for vertical installation in a wall recess and when in such position, including a back, top, bottom and sides and being open at the front, an impervious reflector assembly comprising a vertical concave reflector member and

substantially flat top and bottom closures and being open at the front, said reflector assembly being mounted in said box to define a passage between the lower end of the reflector and the bottom of the box, a vertical passage between the back and sides of the reflector and the back of the box, and a passage between the top of the reflector and the top of the box, said passages being intercommunicating, an impervious substantially horizontal partition across said box near its upper end, the last said passage being defined by the upper face of the reflector top and the lower surface of said partition, open communication from the front of the reflector and box assembly at the bottom thereof leading into the first of said passages and at the top thereof leading from the last of said passages, whereby convection currents may enter below said reflector and travel upwardly between said reflector and said box and be exhausted at the upper forward region of said box and reflector, an electric switch chamber being formed at the upper end of said box by said horizontal partition in the upper terminal parts of said box, an electric resistance heating element mounted in said reflector, electric wiring for said heating element coupled with said switch, and a protective flush-type grill adapted to be mounted upon the wall adjacent the boundaries of the wall recess and in direct association with said box and reflector assembly, said grill being formed with openings near the top and bottom communicating with the said top and bottom horizontal passages which are adapted to convey convection currents, said grill being formed with guard members in front of said electric heating element, the major portion of the metal being removed in parallel lines adjacent to the side edges of said guard members, thereby reducing thermal conductive capacity between the guard members and the side and top flanges of the said grill.

WILLIAM E. CRANSTON, JR.
